UNITED STATES PATENT OFFICE.

WILLIAM R. McCOMAS, OF OAKLEY, ASSIGNOR TO CRANE, BREED & CO., OF CINCINNATI, OHIO.

DESIGN FOR A COFFIN-HANDLE.

SPECIFICATION forming part of Design No. 12,017, dated November 9, 1880.

Application filed August 21, 1880. Term of patent 7 years.

To all whom it may concern:

Be it known that I, Wm. R. McCOMAS, of Oakley, in the county of Hamilton and State of Ohio, have originated a new Design for 5 Coffin-Handles, of which the following is a full, clear, and exact description, reference being had to the accompanying drawing, making part of this specification.

The invention, as represented in the accompanying drawing, I describe as follows:

It consists of a design for the socket of a knuckle-joint coffin-handle.

The socket A is a kaleidoscopic figure of an anomalous outline, B.

15 The ornamentation consists of a modified

six-pointed-star-shaped figure, C, the spaces E between the points of same being appropriately ornamented with laurel-leaves, angles, semicircles, and burnished bands, mainly arcs of circles terminating in other arcs of circles, 20 which form the general outline of the socket A.

What I claim as new, and desire to secure by Letters Patent, is—

The design of a socket or ear of a coffin-handle, as shown and described.

WM. R. McCOMAS.
